(57) **CLAIM**

The ornamental design for a paper roll dispenser as shown and described.

DESCRIPTION

FIG. 1 is a perspective view of a paper roll dispenser showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the paper roll dispenser in use; and,

FIG. 10 is another perspective view of the paper roll dispenser in use.

The portions of the paper roll dispenser shown in broken lines form no part of the claimed design.

The other broken lines illustrate environmental subject matter that form no part of the claimed design.
